TOWNSEND A. NICHOLS, OF WELLSVILLE, KANSAS

STATIONERY BOX

Application filed January 17, 1928. Serial No. 247,437.

The present invention is directed to improvements in stationery boxes.

The primary object of the invention is to provide an article of this kind for use on office desks or at home, the construction being such that various articles, such as paper, envelopes, pens and pencils may be stored conveniently in the box in order that access may be readily had thereto.

Another object of the invention is to provide an article of this kind so constructed that the same can be closed to prevent the entrance of dust.

Another object of the invention is to provide a novel arrangement of partitions to provide compartments of varying sizes and shapes, and further to provide a cover common to all of the compartments.

With these and other objects in view, this invention resides in the novel features of construction, formation, combination and arrangement of parts to be hereinafter more fully described, claimed and illustrated in the accompanying drawing, in which,—

Figure 1 is a perspective view of the box showing the cover in its open position.

Figure 2 is a longitudinal sectional view through the box, the cover being closed.

Referring to the drawing, 1 designates the box which is rectangular in shape, and is provided with a cover 2, said cover consisting of sections 3, 4 and 5, the latter section being fixed to the upper edges of the sides 6 and rear 7 of the box. The fixed section 5 is provided with a recess 8 near its rear edge, the purpose of which will be later explained.

The section 4 is connected to the section 5 by a hinge 9, while the section 3 is connected to the section 4 by a hinge 10. The section 3 has a handle 3' upon its forward end to facilitate opening the cover.

A horizontal partition 11 is fixed within the box and divides a portion thereof into upper and lower compartments 12 and 13, respectively, the former serving to retain letter sized sheets of paper, while the latter is designed to hold legal sized sheets of paper.

The forward end of the partition is provided with an upwardly and forwardly in-

clined strip 14, the purpose of which will appear later.

Mounted upon the partition 11 adjacent the forward end thereof are oppositely disposed trays 15—15 which include spaced side walls 16 and inner end walls 17—17, the partition constituting bottoms for the respective trays, while outer end closures are provided therefor by the sides 6. A wall 18 is fixed between the ends 17—17 in order to provide recesses 19 and 20, the former opening into the top compartment 21 formed by the walls 16—16 and strip 14, said compartment extending transversely of the top in order to provide ample space for the reception of pen holders and pencils. The recess 20 opens into the compartment 12 and by providing these recesses access to the paper contained in the compartment 12 may be readily had, likewise the recess 19 permits ready access to the pen holders or pens in the compartment 21.

Extending transversely of the box 8 and spaced from the forward end 22 is a partition 23 which forms in conjunction with said wall a compartment 24 for the reception of envelopes, said partition forming the front walls of the compartments 25—25, the end walls 26—26 being spaced to provide a recess 27 which communicates with the open end of the compartment 13, the rear walls 27'—27' of the compartments 25 constituting stops for the paper in the compartment 13.

It will be obvious that access can be readily had to the paper in the compartment 13 owing to the presence of the recess 27, said compartment having upon its bottom a tapered block 28 which serves to hold the forward end of the paper sheets elevated slightly to facilitate the removal of a single or small number of sheets.

Fixed to the under surface of the section 4 of the cover is a clip 29 which may be used for holding blotters, cards, a small ruler, or other articles.

The compartments 16 and 25 may be used for holding various articles, such as rubber bands, erasers, paper fasteners, pen points, or in fact, any small article.

Access may be had to the envelope compartment 24 and compartment 25 by merely fold-

ing the cover section 3 upon the section 4, and when access is to be had to the other compartments the sections may be raised and placed in the position as shown in dotted lines in Figure 2, and at which time the free edge of the section 3 engages the recess 8 in order to hold the cover open to permit ready access to the various compartments of the box.

While I have illustrated the box as being made of wood, it will be of course understood that any other material may be used if desired.

To facilitate the removal of the last sheet of paper in the compartment 12, the partition 11 has an opening 30 formed therein which has its rear curved wall disposed rearwardly of the trays 15—15 and since the forward edges of the sheets abut the rear walls 16—16, the sheet can be conveniently grasped upon placing the hand in said opening.

It will be of course understood that the device can be made in various sizes and may be used in a drawer opening of a cabinet or desk. If desired any suitable form of lock may be used in order that the cover 2 may be locked in its closed position.

Having thus described the invention, I claim:

A box for the purpose specified having a horizontal partition fixed therein to provide upper and lower compartments, said partition having an inclined strip upon its forward end, trays mounted upon the partition and forming in conjunction with said strip a compartment, said trays having their inner ends spaced to provide recesses opening into the upper compartment, and the last named compartment, said partition having an opening formed therein, as and for the purpose set forth.

In testimony whereof I affix my signature.
TOWNSEND A. NICHOLS. [L. S.]
